CLAIM

The ornamental design for an archery limb cup, as shown and described.

DESCRIPTION

FIG. 1 is an angled isometric view of the archery limb cup. FIG. 2 is a top view of the archery limb cup.

FIG. 3 is a bottom view of the archery limb cup.

FIG. 4 is a left side view of the archery limb cup.

FIG. 5 is a right side view of the archery limb cup.

FIG. 6 is a back view of the archery limb cup; and,

FIG. 7 is a front view of the archery limb cup.

The broken lines in the Figures are for illustrative purposes only. The broken lines form no portion of the claimed design.
